Primary Examiner — Mitchell I. Siegel*(74) Attorney, Agent, or Firm* — Randy K. Chang**CLAIM**

The ornamental design for a weight for a golf club grip, as shown and described.

DESCRIPTION

FIG. 1 is a perspective view of a weight for a golf club grip showing our design;

FIG. 2 is a top plan view thereof;

FIG. 3 is a perspective view of the weight for a golf club grip thereof, having the grip removed;

FIG. 4 is a side view of the weight for a golf club grip thereof, having the grip removed;

FIG. 5 is a bottom view of the weight for a golf club grip thereof, having the grip removed; and,

FIG. 6 is a cross sectional view of the weight for a golf club grip thereof.

The broken lines showing the external grip and fragmented shaft form no part of the claimed design.
